UNITED STATES PATENT OFFICE.

ERNEST HENRY STILL, OF LONDON, ENGLAND.

COFFEE INFUSER.

Application filed February 16, 1925. Serial No. 9,654.

To all whom it may concern:

Be it known that I, ERNEST HENRY STILL, a subject of the King of Great Britain and Ireland, residing at London, England, have invented Improvements in Coffee Infusers, of which the following is a specification.

This invention has reference to coffee infusers of the type in which hot water from a boiler under pressure passes through ground coffee contained in a suitable receptacle.

With such apparatus if the infusion period is prolonged and the temperature of the water is at or about boiler temperature (say about 200° F.), it is found that the coffee becomes a bad colour when in the cups.

The object of this invention is to enable this disadvantage to be overcome and for this purpose the hot water, instead of passing directly from the boiler to the infusing receptacle, is led through a cooling device, which is adapted to reduce the temperature of the water coming from the boiler (for instance to about 160°-180° F.) before reaching the coffee in the infusing receptacle.

The cooling device may be in various forms. In some cases it may be a coil or chamber exposed to the air or it may be in the form of a series of tubes contained in a casing, the hot water passing through the tubes and air flowing through the casing around them and, in order to regulate or vary the cooling effect automatically, a diaphragm or expandible capsule exposed to the hot water is adapted, in the event of the water not being sufficiently cooled after passing through the cooling device, to open a damper controlling the flow of air through the casing; the additional flow of air will reduce the temperature of the water and, on the diaphragm accordingly contracting, the damper will more or less close.

The control cock is arranged between the boiler and the cooling device.

The present invention is applicable to apparatus of a kind commonly used in restaurants, a portion of one well known form of which has been chosen for illustration in the accompanying drawings in further describing the invention.

Of these drawings, Figs. 1 and 2 are elevations at right angles to one another showing one arrangement, Fig. 1 being partly in section and drawn to a larger scale than Fig. 2. Fig. 3 is a view corresponding to Fig. 2 of another arrangement, Fig. 4 is a

view at right angles to Fig. 3 of a portion of the latter and Fig. 5 is a section on the line 5—5 Fig. 3. Fig. 6 is a sectional view of a part of Fig. 1 to the same scale as Fig. 2. Fig. 7 is a part sectional elevation corresponding to Fig. 1 of a further modification.

Referring first to Figs. 1, 2 and 6, the pedestal 1 which, as before, has two steam branches 2 leading to the jackets 3 of infusion receivers 4 and a control cock 6 has a water way 7 which in lieu of directly entering the infuser 8 that surmounts the portion 9 of the pedestal 1 is diverted, as by an obstructing screw plug 10, so that it passes through a lateral passage 11 to the inlet end 12 of a cooling element 13, and the outlet end 14 whereof leads through a passage 15 to that portion 16 of the water way that is above the plug 10. The element 13 as will be seen, is of oval shape in cross section. A nonreturn ball valve 17 is shown as inserted in the passage 16.

In the alternative arrangement shown in Figs. 3, 4 and 5, a number of straight tubes 18 extend between plates 19, 20 in a casing 21, the plate 19 forming with the bottom 22 of the casing a chamber connected by piping 23 to the passage 11 of the pedestal 1, and the plate 20 forming with another plate 24 a chamber connected by piping 25 to the passage 15 of the pedestal. Air is admitted to the casing 21 by holes 26 and passes through tubular vents 27 to the chamber 28 which is equipped with a hinged lid 29 acted upon near its hinge by a lever 30 of well known type associated with a thermostatic capsule 31 in contact with the plate 20 which may for this purpose conveniently be dished as shewn.

To regulate the flow of water through the water way, a screw such as shown at 32* in Fig. 6, may be employed.

In the modification shown in Fig. 7 the control cock 6* is adapted, as in the other cases, to admit hot water to the passageway 7* which however communicates through a port 11* with a chamber 32 constituted in part by a false bottom 33, a dished baffle 34 in the chamber 32 serving to cause the water to be diverted radially inwards under the bottom of the infuser 8* and to subsequently escape by passage 15* to the waterway 16* beyond the obstruction 10* and so past the ball valve 17* into the infuser.

The bottom member 33 is shown as

equipped with fins 35 to assist in obtaining the desired cooling.

What I claim is:—

1. In coffee making apparatus of the kind in which water from a boiler under pressure is forced through the bottom of an infuser, an infuser pedestal formed with a vertical water way, a water cooler connected at two points in the water way and an obstruction 10 in the latter adapted to bye-pass the water through the water cooler, substantially as described.
2. In coffee making apparatus of the kind in which water from a boiler under pressure is forced through the bottom of an infuser, an infuser pedestal formed with a vertical water way, said pedestal constituting a false bottom for such infuser and forming with the latter a cooling chamber, said pedestal 15 having further a water way through which

water may be caused to enter the infuser, and obstructing means adapted to cause the water to leave the water way, flow through the cooling chamber and again enter the water way so that it enters the infuser reduced in temperature. 25

3. In coffee making apparatus of the kind in which water from a boiler under pressure is forced through the bottom of an infuser, an infuser pedestal, constituting a false bottom for such infuser and forming with the latter a cooling chamber, heat radiating members upon the exterior of such bottom and means for conducting hot water through the pedestal by way of the cooling chamber, 30 substantially as described. 35

Signed at London, England, this 26th day of January, 1925.

ERNEST HENRY STILL.
